CLAIM

The ornamental design for a fluid dispensing module for
dispensing heated fluids, such as hot melt adhesive, as
shown and described.

DESCRIPTION

FIG. 1 is a perspective view of a new design for a fluid
dispensing module for dispensing heated fluids, such as
hot melt adhesive;

FIG. 2 is a front, elevational view of the fluid dispensing
module for dispensing heated fluids, such as hot melt
adhesive of FIG. 1;

FIG. 3 is a side elevational view thereof;

FIG. 4 is a back, elevational view of the fluid dispensing
module for dispensing heated fluids, such as hot melt
adhesive of FIG. 1;

FIG. 5 is a top elevational view thereof; and,

FIG. 6 is a bottom elevational view thereof.
